John Davis
Atticus Patent

1860 X

The schedule referred to in these Letters patent and making part of the same containing a description, in the words of the said John Davis, himself of his improved Caboose.

The general form of the Caboose is square like others, but the front is closed except near the bottom where there is an opening the whole length, the front of a sufficient height which communicates to the grate or fire on each side of the bottom where the fire is, are two checks of cast iron, made in a form sloping towards the centre of the grate, that is placed between them the sides resting in the lower parts of the above mentioned sloping checks, said checks being hollow prevent the heat of the fire from communicating to any part of the vessel near the Caboose, and the space between is occupied by a grate of sufficient depth. Immediately over said opening in front of the Caboose is the oven, projecting inwards and over the fire, of a sufficient size immediately over the oven is the mouth, the flue which occupies the space of the whole front of the caboose - formed by a double plate placed at the space of about two inches from the front plate, contracting gradually over the top of the Caboose, terminating by a flue or pipe of six inches which rises an about at 10. The space at the back of the oven is occupied by the boiler, the bottom which is within two inches of the middle plate, the top of the boiler which lies with the top of the oven receives two perforated Nozzles which occupy the whole inside space of the Caboose, and cause any victuals being laid thereon, to be cooked by the steam from the boiler.

The whole Caboose has a lid or cover, which cover has a smaller aperture in the centre stopped by a lid, for the purpose of looking in at pleasure.
